his ATTORNEYS.

UNITED STATES PATENT OFFICE.

JAMES L. BREESE, JR., OF LAKE FOREST, ILLINOIS, ASSIGNOR TO OIL DEVICES CORPORATION, OF CHICAGO, ILLINOIS, A CORPORATION OF ILLINOIS.

MEANS FOR BURNING LIQUID FUELS.

Application filed February 21, 1925. Serial No. 10,742.

My invention has been developed in connection with the combustion of petroleum oils and is especially useful therefor though, as will be obvious from the following disclosure, it is applicable generally to combustible liquids of a similar nature. I have employed the invention successfully in connection with what is known commercially as gas oil. The invention is applicable generally to the purpose of heating by the combustion of liquid fuel such as for heating rooms, boilers and the like. The apparatus in which my invention is embodied is a wickless burner adaptable to a great variety of heating purposes, efficient, easy to operate and regulate and relatively inexpensive to manufacture. In this burner the oil is vaporized for burning by a conductor of heat which in turn is heated by the combustion of the vapors formed and conveys the heat to the body of fuel oil, the amount of oil vaporized being regulated and controlled not only by the temperature of the conductor but also by the extent to which the latter is in contact with the body of oil from which the vapors are generated. In the specific structure disclosed the conductor dips into the body of oil and the extent of surface contact is regulated by the level of the oil. The oil level, so long as the temperature of the article, compartment or the like being heated remains substantially constant, is likewise maintained substantially constant this being effected in the specific apparatus disclosed by a valve controlled jointly by a float and thermostat and variations in temperature are reflected in the liquid level by means of a thermostat which influences the degree of immersion of the float controlling the valve, varying according to the temperature to which the thermostat is subjected, and thereby varying correspondingly the level of the body of oil being vaporized. Other features of the invention will be understood from the following detailed description taken in connection with the drawings accompanying and forming part of this application. It is to be understood, however, that the specific disclosure is for the purpose of exemplification only and the scope of the invention is defined in the following claims in which I have endeavored to distinguish it from the prior art so far as known to me without however relinquishing any of the novelty disclosed.

In the drawings Fig. 1 is an elevation

partly in section showing a heater with my invention applied thereto; Fig. 2 an axial vertical section partly in elevation through the lower part of the heater and through the burner; Fig. 3 a fragmentary view on the same plane as Fig. 1, a portion of the burner being shown in elevation instead of in section; Fig. 4 a plan of my improved burner; Fig. 5 a vertical section partly in elevation showing the means for controlling the height of the liquid fuel in the burner and Fig. 6 a plan view thereof. Each part is identified by the same reference character wherever it occurs in the drawings.

In Fig. 1 I have shown my invention as applied to a heater which is entirely self-contained except for the flue and may be set up wherever required for use by merely connecting up the flue in a proper manner to dispose of the products of combustion. This form of heater is not per se novel or of my invention but it is disclosed only to exemplify the latter. It comprises a drum 7 into the lower end of which my improved burner 8 extends and from the upper end of which the flue 9 leads to some proper outlet for the products of combustion. I have shown the burner and heater as mounted on a sheet metal support 11 which is extended vertically at 12 to form a reflector or shield. The flue 9 is shown as elbowed and partially supported by the top of the shield and by the brace 13. A strap 14 holds the flue in a recess cut in the top edge of the shield. Beyond the shield the flue extends vertically as at 15 to some suitable outlet. The flue is provided with a balanced or butterfly damper valve 16 and an unbalanced damper 17, the two being so connected by link 18 that increased draft tending to lift or open the damper 17 tends to partially close damper 16.

As stated, the specific form of heater forms no part of the present invention.

The burner is shown as mounted on a tripod casting 18 with respect to which it is adjustable by means of a set screw 20. The burner housing casting 19 comprises a central sleeve 27 extending into said tripod casting, a portion of intermediate diameter forming the oil reservoir 21 and an upper portion of enlarged diameter 22. The sleeve 27 is continued upwardly through the oil reservoir to form an air passage to supply primary air to the combustion chamber.

An annular casting 29 which constitutes the combustion chamber and also the means for conducting heat therefrom to the oil to vaporize the latter rests upon the shoulder 5 between the oil reservoir and the upper chamber. Said casting comprises a horizontal annulus 29^a, a depending flange 30 and an upwardly extending annular flange 39. The depending flange is tapered as 10 shown in Fig. 2 and spaced from the central sleeve 27. In use the oil reservoir is filled to a level at which the flange dips more or less into the oil therein and vaporizes the latter by means of the heat transmitted from 15 the combustion chamber. The vapors rising from the oil pass upward through the converging annular passage between said flange and the sleeve 27 into the combustion chamber. The flange is slotted or divided into 20 lugs as at 30^a, see Fig. 3, to provide access to said passage of the vapors arising around the outside of the flange. As will appear later on in the specification, provision is made for controlling the level of the liquid 25 and thereby regulating the vaporization of the oil.

As above stated, the combustion chamber is enclosed by the upwardly extending flange 39 forming a part of the casting just described. Said flange is of materially less diameter than the upper chamber in which it is located so that there is an annular air space surrounding the same, and the wall of chamber 22 is notched as at 41 for the admission of air to said annular space. Flange 39 is slotted at short intervals, the slots being tangential as best shown in Fig. 4, the inclination being all in the same direction, so that air entering through the notches 40 41 into the annular passage 22 enters therefrom into the combustion chamber through the inclined slots. It is thus given a whirling motion and not only furnishes the secondary supply of air for complete combustion but shrouds or shields the flange from the direct action of the flame. The entering air also more or less cools the flange, the extent of cooling depending somewhat upon 45 the size and number of the slots. Therefore by suitably designing this flange the temperature conditions of the burner may be varied somewhat.

A deflector or spreader plate 32 is adjustably mounted above the end of the sleeve 27, in the construction shown being carried by a rod 33, the upper end of which is held centrally in the sleeve by screws 34 and the lower end supported at 35 on a bracket 36 which is pivoted at 37 and adjusted about 50 its pivot, to raise or lower the deflector plate 32 by means of a set screw 38.

When the burner is in operation, a primary supply of air is received through the sleeve 27 and flows upwardly therein as indicated by the arrows and then is deflected

outwardly by the deflector plate previously described. The heat conducting casting 29 dipping into the oil in the oil chamber generates vapors therefrom which flow upwardly in the annular space between said heat 70 conducting casting and the sleeve and mix with the air coming through the sleeve beneath the edge of the deflector plate. The air supplied in this manner is insufficient for complete combustion, but additional supplies 75 of air are received, through the openings 41 into the annular space about the flange 39 and enter the chamber within the flange through the slots or slits previously described. The air entering the slots being 80 given a rotary motion by the inclination thereof forms a cushion or envelope which more or less fully protects the flange from the flames and also furnishes the additional air necessary to complete combustion. The 85 outer wall of the combustion chamber is protected from the extreme heat of combustion by the air entering the ports 41. The conduction of heat from the heat conducting plate 29 to the wall of the casting 19 may be 90 made negligible by providing substantially a line contact between the two as at 29^a. When this is done, the oil in the reservoir receives little heat except through the vaporizing conducting casting 29. 95

The level of the oil in the reservoir and hence the amount of vaporization is controlled according to the temperature which it is desired to maintain. Thus in the heater in connection with which my invention is disclosed and which is designed for heating the air of rooms and other compartments the feed of oil is mainly regulated by the temperature of the air. Referring to Figs. 1, 5 and 6, the feed regulator 45 is shown as 100 connected to the supply pipe 46 on the one hand and to the oil reservoir of the burner on the other. Pipe 47 affords an open connection between the regulator and the burner being connected at one end as at 48 to the bottom of the float chamber of the regulator and at the other end at 49 to the oil reservoir of the burner. The oil supply pipe 46 is connected to the regulator at 50, communication being controlled by a valve 51 seated at 52. A float 53 which is free to rise and fall in the chamber of the regulator controls the valve through the medium of a lever 54 pivoted at 55. Lever 54 is pivoted to the stem 56 of the float and the latter is guided in a sleeve 57 secured to the cover 58 of the regulator chamber. 110

In order that the level of the liquid may be automatically controlled according to the temperature I provide a thermostat 59 which is secured at one end as at 60 to a bracket 61 threaded on guide 57. The other end of the thermostatic strip 59, which may be of the usual form comprising two strips of metal of different coefficients of expansion 125 130

sion, is secured to the stem of the float at 62. The thermostatic strip 59 is so arranged that with increase of temperature it tends to raise the float and with decrease of temperature to lower the same. It follows that when the temperature rises beyond that for which the apparatus is set the valve is closed and the level of oil in the regulator and oil reservoir of the burner falls with the consumption of oil. As the oil level falls in the oil reservoir the amount of oil vaporized diminishes by reason of the reduction of area of the heat conductor covered by the oil. As the temperature falls the upward pull of the thermostat is reduced and the valve opens. It should be understood that the thermostatic leaf preferably operates with a force of the same general order of magnitude as that exerted by the float itself. Under some conditions the action of the leaf may be opposed to the action of the float, and under other conditions it may supplement it. Thus the valve 51 is to some degree responsive to two forces, namely to the tendency of the float 53 to open or close it, and to the tendency of the thermostatic leaf 59 to open or close it. Under normal conditions, when the two forces are opposed, neither can entirely overcome the other and the balance of forces leaves the valve in an intermediate position. The effect of the thermostat may be varied to provide for the maintenance of different temperatures by turning the thermostat and bracket about the guide to which the latter is threaded to adjust it nearer to or further from source of heat.

Because of its location, as shown in Fig. 1, the thermostat is exposed to the currents of air flowing to the burner from the atmosphere of the room or compartment being heated so that it responds to the average temperature of the compartment. It is also exposed to some extent to direct radiation from the burner. It thus serves to control excessive temperatures in the latter.

To start the burner it is only necessary to apply a flame to the combustion chamber, as, for example, by introducing a lighted paper or other combustible material. The combustion of the oil on the surfaces of the burner in connection with that of the introduced combustible material is sufficient to start vaporization and combustion of the oil.

While I have described the burner with its feed in connection with an apparatus for heating the air of a room or other enclosure, I have done so for the purpose of exemplification only as the burner is available for a variety of heating purposes, as for example, heating boilers and hot water heating systems.

I claim:

1. In a burner of the class described, a

chamber for containing a body of oil, a combustion chamber above the same, a heat conductor intermediate the combustion chamber and oil chamber and extending into the latter to vaporize oil therein, a thermostat, and means controlled jointly by the thermostat and the level of the oil in the oil chamber for feeding oil to the latter. 70

2. In a burner of the class described, a chamber for containing a body of oil, a combustion chamber above the same, means for feeding the fuel from the oil chamber to the combustion chamber in accordance with the level of the oil in the oil chamber, and means for supplying the oil chamber with oil comprising a float and valve chamber, a float therein, a valve governing the inlet to said chamber and controlled by the float, a thermostat and connections between the thermostat and float whereby the thermostat tends to close the valve as the temperature rises. 75

3. In a burner of the class described, a combustion chamber and an oil chamber communicating therewith, means for vaporizing the oil, the extent of vaporization depending on the level of the oil, and means for supplying the oil chamber with oil comprising a conduit, a float and valve chamber in the conduit, a valve in said chamber controlling the admission of oil thereto, a float in said chamber controlling the valve, a thermostat comprising two strips respectively of different metals supported at one end and engaging the float at the other, the construction being such that as the temperature rises the thermostat tends to raise the float. 90

4. In a burner of the class described, a combustion chamber and an oil chamber 105 communicating therewith, means for vaporizing the oil, the extent of vaporization depending on the level of the oil, and means for supplying the oil chamber with oil comprising a conduit, a float and valve chamber 110 in the conduit, a valve in said chamber controlling the admission of oil thereto, a float in said chamber controlling the valve, a thermostat comprising two strips respectively of different metals supported at one 115 end and engaging the float at the other, the construction being such that as the temperature rises the thermostat tends to raise the float, and means to adjust the thermostat. 120

5. In a burner of the class described, a combustion chamber, a fuel passage extending thereto, a fuel flow control means in said passage, including a float chamber and a float therein, a valve adapted to control the flow of fuel to said chamber, an actuating connection between said float and said valve, a thermostatic member and an actuating connection between said thermostatic member and said float. 125

6. In a burner of the class described, a 130

combustion chamber, a fuel passage extending thereto, a fuel flow control means in said passage, including a float chamber and a float therein, a valve adapted to control the flow of fuel to said chamber, an actuating connection between said float and said valve, a thermostatic member and an actuating connection between said thermostatic member and said float, the force exerted by the thermostat being of the same general order of magnitude as that exerted by the float.

7. In a burner of the class described, a combustion chamber, a fuel passage extending thereto, fuel flow control means in said passage, including a float chamber and a float therein, a valve adapted to control the flow of fuel to said chamber, an actuating lever connection between said float and said valve, a thermostatic leaf adapted to flex in response to changes in the temperature to which it is exposed and an actuating connection between said leaf and said float.

8. In a burner of the class described, a

combustion chamber, a fuel passage extending thereto, fuel flow control means in said passage, including a float chamber and a float therein, a valve adapted to control the flow of fuel to said chamber, an actuating connection between said float and said valve, a stem extending from said float and through the wall of the float chamber, a thermostatic member and an actuating connection between said member and said stem.

9. In a burner of the class described, a combustion chamber, a fuel passage extending thereto, fuel flow control means in said passage, including a float chamber and a float therein, a valve adapted to control the flow of fuel to said chamber, an actuating connection between said float and said valve, a stem extending from said float and through the wall of the float chamber, a thermostatic member and an actuating connection between said member and said stem, and means for adjusting the connection between said thermostatic member and said stem.

JAMES L. BREESE, JR.
